HIGH FREQUENCY AMPLIFIER CIRCUITS

Maximiliaan Julius Otto Strutt and Aldert van der Ziel, Eindhoven, Netherlands, assignors to Radio Corporation of America, a corporation of Delaware

Application May 3, 1940, Serial No. 333,088
In the Netherlands July 25, 1939

2 Claims. (Cl. 179—171)

This invention relates to circuit arrangements for amplifying electric oscillation, use being made of an electron discharge tube having at least a cathode, a control grid and an anode, and the cathode being provided with at least two leads, one of which is included in the control grid circuit and another in the anode circuit.

It is a well known phenomenon, which stands out particularly in the amplification of very short waves, that the cathode lead of a high frequency amplifier tube can bring about substantial damping of the input circuit due to the fact that the impedance of the cathode lead is common for the grid and anode circuits. It is, also, known that this damping effect of the cathode lead can be avoided by providing the cathode with at least two leads, one of which is included in the control grid circuit and another in the anode circuit. In this case the input damping which is particularly important with short waves is maintained, due to other causes, for example the finite transit time of the electrons. This damping is approximately proportional to the square of the frequency, and consequently increases rapidly with shorter waves. For this reason it is insufficient with short waves to eliminate the damping due only to the common impedance of the cathode lead, and it is desirable that the entire damping between the input terminals of the discharge tube should be suppressed, or even made negative, and in this latter case the negative damping can be used for entirely, or partly, compensating the damping due to the preceding amplifier tube and/or the damping of the impedances connected between the said input terminals.

According to the present invention this result is obtained with tubes having at least two cathode leads, one of which is included in the control grid circuit and another in the anode circuit, due to the fact that between the control grid and the point of the cathode which is connected to the cathode lead included in the control grid circuit and between the control grid and that point of the cathode lead included in the anode circuit which is not connected to the cathode, capacities are present, and in one or both cathode leads impedances are present at least one of which has an inductive character, said capacities and impedances being such that the damping between the input terminals of the discharge tube is substantially zero or negative.

In order that the invention may be clearly understood and readily carried into effect it will now be described more fully with reference to the accompanying drawing in which Fig. 1 shows one

embodiment of the invention. Figs. 2 and 3 show modifications.

Referring now to Fig. 1, numeral 1 designates an amplifier tube comprising a cathode 2, a control grid 3, auxiliary electrodes 4 to 6 and an anode 7. The cathode is provided with two leads

5 having included in them impedances shown in this figure as inductances L_1 and L_2 . Between the control grid 3 and the point 8 of the cathode which is connected to the cathode lead included in the control grid circuit there is a capacity C_1 . Between the control grid 3 and the point 9 of the cathode lead, included in the anode circuit that is not connected to the cathode, there is a capacity C_2 . V_1 designates the input voltage to be amplified which is supplied between the input terminals 10 and 11. For the sake of simplicity the input and output circuits themselves and the supply sources of direct current are not shown.

10 For the most general case we assume that the tube 1 contains a secondary emission cathode having a mutual conductance of the secondary emission current going to the anode as a function of the control grid voltage equal to $-S_h$ and that this auxiliary cathode is connected, for the oscillations to be amplified, to the lead to the input circuit. The cases where an auxiliary cathode is not present can be derived from the general case by assuming $-S_h$ to be equal to zero.

15 The angular frequency of the oscillations to be amplified will be termed ω , the mutual conductance of the cathode current as a function of the control grid voltage will be termed S_k . In C_1 the control grid-cathode capacity and in C_2 20 the capacity between the control grid and the auxiliary electrode or electrodes and the anode which are connected to point 9 are discounted. It is assumed that the mutual conductance of the auxiliary electrodes connected to 9 is negligible.

25 Now, the invention makes available the fact that between the admittance Y_0 which occurs between the input terminals 10 and 11 of the discharge tube and the values ω , S_h , S_k , L_1 , L_2 , C_1 and C_2 the following relationship exists:

$$40 Y_0 = -\omega^2 [S_h L_1 (C_1 + C_2) + (S_h + S_k) L_2 C_2] \quad (1)$$

45 This impedance is negative, and can be used with a given tube by correct choice of the values L_1 , L_2 , C_1 and C_2 for entirely, or partly, compensating the damping due to the transit time of the electrons, and in addition the damping due to the preceding amplifier tube, and/or the damping of the impedances included between the input terminals 10 and 11. Since the damping of the 50 input circuit is approximately also proportional

to ω^2 this compensation is secured to a large frequency range.

In practice the most simple case in this respect is where a tube does not contain a secondary emission cathode so that $-S_h=0$, and in this case the admittance

$$Y_0^0 = -\omega^2 S_k L_2 C_2 \quad (2)$$

In this case the inductance of the cathode lead 8-11 and also the value of the capacity C_1 is immaterial and thus the damping reducing effect is practically only governed by the inductance L_2 and the capacity C_2 and also by the mutual conductance S_k . The capacity C_2 may be the anode-grid capacity in the case of a triode and the anode-control grid + screen grid-control grid capacity (approximately therefore the screen grid-control grid capacity) in the case of a tetrode, and so forth, without there being supplementary capacities deliberately provided.

According to the invention, in this case the value of L_2 must be such in connection with the values of the capacity C_2 and of S_k that the damping reducing effect according to formula (2) is equal to, or exceeds, the damping due to the transit time of the electrons. Such a circuit arrangement is shown in Fig. 2 in which C_3 represents a filter condenser.

Alternatively, it may be assumed that L_2 represents the inductance of the lead and according to the invention it is in this case necessary for C_2 to be increased by means of supplementary capacities in such manner that the value of Y_0^0 according to formula (2) is equal to, or exceeds, the damping due to the transit time of the electrons. According to formula (1), if the tube is provided with a secondary emission cathode the inductance L_1 and the capacity C_1 do play a part so that this should be taken into account. A tube of this kind is diagrammatically shown in Fig. 3, the same numerals designating corresponding parts of Figs. 1 and 2. In addition, U_2 designates the source of supply voltage for the secondary emission cathode S_h . In this case (see also Fig. 2) C_1 may be, for example, the control grid-cathode capacity and C_2 the screening grid-control grid capacity without any other capacities being deliberately provided. According to the invention, in this case L_1 and L_2 respectively may be such that according to formula (1) Y_0^0 is equal to, or exceeds, the damping due to the finite transit time of the electrons. As before, the inductances of the cathode leads themselves may be chosen to constitute L_1 and L_2 and in this case the capacities C_1 and/or C_2 are increased in such manner by deliberately provided supplementary capacities that the desired effect according to the invention is obtained.

In both cases the capacities as well as the in-

ductances can obviously be increased artificially in order to obtain the desired effect. By comparing formula (1) with formula (2) it is evident that in the use of a secondary emission tube, due to the mutual conductance of the secondary emission current, the same means permit of obtaining an appreciably higher damping-reducing effect than with a tube without such an auxiliary cathode. In the circuits shown the two cathode leads are always connected to different sides of the cathode. This is, however, not essential, but the two leads may also be connected, for example in common, to one point of the cathode. It is, also, obvious that the invention can be used without difficulty for tubes comprising three or more cathode leads, and in this case, for example in the event of three cathode supply conductors, the third one is used for other purposes.

What is claimed is:

1. A circuit for the amplification of high frequencies, comprising an electron discharge tube provided with at least a cathode having two external terminals, a signal input grid and an anode, the cathode having a lead connected to each of its external terminals, input and output circuits connected respectively to the input grid and to the anode, the grid return of the input circuit being connected to one of the cathode leads, the plate return of the output circuit being connected to the other cathode lead, a condenser connected from the signal input grid to a point having the same radio frequency potential as said plate return, and an inductance included in the cathode lead to which the plate return is connected, the condenser and inductance being chosen of such value that damping between the terminals of the input circuit is substantially zero.

2. A circuit for the amplification of high frequencies, comprising an electron discharge tube provided with at least a cathode having two external terminals, a signal input grid and an anode, the cathode having a lead connected to each of its external terminals, input and output circuits connected respectively to the input grid and to the anode, the grid return of the input circuit being connected to one of the cathode leads, the plate return of the output circuit being connected to the other cathode lead, an inductance included in the latter cathode lead, and a condenser between the control grid and the end of said inductance remote from said cathode, the product of the values of said inductance and condenser being sufficiently great that positive conductance is eliminated from the input admittance of said tube.
